UNITED STATES PATENT OFFICE

2,641,326

PORTABLE FEED GRINDER CARRIER

Le Roy Carlson, Griswold, Iowa

Application August 8, 1950, Serial No. 178,324

1 Claim. (Cl. 180—14)

1

This invention relates to a portable farm feed grinder and more particularly to a carrier frame adapted to receive a stationary feed grinder thereon for converting it to a portable grinder.

A general object is to increase the over-all efficiency and utility of ordinary farm feed grinders.

A further object is to provide a carrier adapted for attachment to a powered farm mechanism for transporting a feed grinder to the source of the grains to be ground thereby reducing the time and expense usually involved in grinding operations.

Inasmuch as grinders must be kept level to operate efficiently, it is a further object of this invention to provide a carrier frame adapted for attachment to a powered farm mechanism and to receive a grinder and which can be adjusted from either end to keep the grinder level on various types of terrain and in variant weather conditions.

Another object of this invention is to produce a portable farm feed grinder which occupies less space than that usually occupied by a stationary farm feed grinder and which is easily and inexpensively assembled.

It is a further object of this invention to provide a carrier having an adjustable bed adapted to receive grinders of various sizes.

A further object of this invention is to assemble a portable farm feed grinder having a relatively short non-slip continuous pulley belt.

Further objectives and advantages in this invention may be readily ascertained from the following specifications and attached drawings in which:

Fig. 1 is a perspective view showing the carrier attached to a farm tractor and having the grinder mounted thereon.

Fig. 2 is a side view of the carrier.

Fig. 3 is a plan view of the carrier.

Fig. 4 is a front view of the carrier.

While this invention is susceptible of various modifications and alternative constructions, it is shown in the drawings and will hereinafter be described in a single preferred embodiment. It is not necessarily intended, however, that the invention is to be limited thereby to the specific construction disclosed. On the contrary, it is intended to cover all the modifications and alternative construction falling within the spirit and scope of the invention as defined in the appended claim.

Heretofore the grinding of farm feeds has generally been accomplished on stationary farm feed grinders. In most cases the grinder was first per-

manently affixed to a barn floor. When grinding was necessary, a piece of mobile farm power machinery was placed substantially in line with the stationary grinder and a relatively long pulley belt was run from a drive pulley shaft on the power machinery to a driven pulley shaft on the grinder. In many cases the belt was as long as 22 to 32 feet. The belt often sagged, twisted and, of course, was accompanied by slipping. It was also necessary for a person grinding feed to transport the feed from its source to the grinder mechanism and oftentimes it was then necessary to transport the ground feed back to the source.

It became essential therefore to discover some method for taking the grinder to the source of the feed in order to grind grain on the spot. This was relatively difficult because of the differences in terrain near the various sources of supply for grains which caused the grinder to be in an unlevel position. A stationary hammer mill grinder generally must be kept level in order for it to operate efficiently.

I have invented a carrier which overcomes the inefficiency of stationary feed grinding and the obstacles heretofore confronting one attempting to grind feed at its source.

My invention comprises generally a carrier frame 3 adapted to receive an ordinary hammer mill grinder 2 thereon. The carrier frame 3 mounts a vertically adjustable wheel 22 at the rear end thereof and has vertical frame members 5 near the front end thereof adapted for engagement with a piece of mobile farm power machinery.

More particularly, this carrier frame 3 comprises a pair of parallel, longitudinally extending bed members 4 spaced apart and having bolt holes 11 drilled therein to receive the four corners of an ordinary hammer mill grinder.

The carrier frame is movably supported at its rear end by wheel 22. Because one purpose of this carrier is to provide a carrier which is adjustable from either end, the wheel 22 is adapted to be adjustable vertically. To that end, wheel standards 10 are supported on the rear ends of bed members 4 and form journals for the axle of wheel 22. Each wheel standard has a plurality of vertically positioned journal connections 28 for raising or lowering the wheel. Such adjustment not only aids in levelling the frame but also allows for attachment to variously sized farm power machinery. It is not contemplated that much adjustment will be necessary at the rear end of the carrier, hence it is designed to be manually adjustable.

The front end of the carrier device is also to

be raised and lowered to keep the grinder level. To this end, the carrier is equipped with a pair of parallel upright channel members 5 spaced apart and adapted to be connected by means of pins 21 located near the top of the upright members 5 to a set of standard tractor lifter arms 17 which are affixed to the rear end of the tractor. The lifter arms 17 have connected thereto cranks 20 which when rotated either raise or lower the lifter arms and hence the carrier depending on the direction of rotation. The upright channel members 5 are supported on a cross channel member 6 which extends horizontally across the front end of bed members 4 at right angles thereto and generally in the same plane.

Raising and lowering the carrier is vitally necessary to the efficient operation of the feed grinder since they keep the grinder level regardless of the condition of the terrain and regardless of certain weather conditions which would cause a grinder of this type to set in an unlevel position. For instance, if the rear wheel of carrier 3 were in a depression in the soil, it is possible that some point along the longitudinal bed members 4 might rest on a higher point of the terrain and thereby cause the carrier and grinder to be out of a level position. With the portable feed grinder as shown, however, it would be possible to draw the rear wheel to a higher point of the terrain and to raise the front end of the carrier to correspond therewith or it would be possible to adjust the rear wheel to raise the rear end of the carrier above the ground to correspond with the position of the front end of the carrier. Hence, by adjusting either the front or rear end of the carrier, it is possible at all times to keep the carrier and grinder level and to obtain a grinder of a portable nature and of increased efficiency.

The operative power for the grinder is provided by a transmission connection from a drive pulley shaft 18 on the powered farm device to a driven pulley shaft 19 on the grinder shown here as a relatively short continuous 6" pulley belt 16. The length of the belt may vary slightly according to the various grinders and farm power machinery used, but it is shorter than the belts used in stationary feed grinding.

Once the belt is installed the distance between the drive and driven shafts remains fixed, hence an outside source of tension for the belt is provided. To accomplish this, journal blocks 12 are slidably attached on the inside surfaces of the upright channel members 5. The journal blocks are adjustable vertically of the upright members 5. Such vertical movement is imparted by crank 15 mounted on top of the upright channel members and connected to the journal blocks 12 by screw shaft 23. Intermediate the journal blocks and journaled therein at each of its ends is a bar 13 having mounted thereon a longitudinal adjustable cylindrical drum 14. Movement of the cylindrical drum longitudinally of bar 13 and movement of the journal blocks 12 vertically cooperate to bring the cylindrical drum 14 into engagement as an idler pulley with the pulley belt 16.

It is conceivable that a single user of the present carrier may have more than one grinder or other devices having different sized bases. To accommodate these variously sized bases, this carrier is provided with a third longitudinal channel bed member 25 parallel to bed members 4 and lying in the same plane. The member 25 is ad-

justable laterally of the carrier and has bolt holes drilled therein for attachment of the base of a grinder or the like. Bed member 25 has one end of its channel closed and adapted to be bolted to the inside leg of cross channel member 6. To accomplish this the inside leg of cross channel member 6 has cut thereon a relatively long slot 26. At its other end adjustable bed member 25 is supported by a cross base member 8 disposed at right angles to the bed members 4. A slot 27 is also cut into the base of cross base member 8. The slots are substantially aligned. To insert the adjustable bed member 25 the closed channel end is bolted against the inside leg of cross channel member 6, and the other end is bolted beneath cross base member 8. By loosening the bolts so holding the adjustable bed member in place it can be adjusted laterally of the bed and then tightened in place at its new position.

To impart rigidity to the carrier frame 3 it is provided with braces 7 which extend angularly between upright channel members 5 and the ends of cross channel member 6, said ends of cross channel member 6 extending beyond the point of support for the upright channel member 5. Also a relatively long brace member 9 is affixed between one of the upright members 5 and one end of the cross base member 8 set across and at right angles to the longitudinal bed member 4. The other end of cross base member 8 extends freely beyond the longitudinal bed member 4. Brace 9 also acts as a guard for the pulley belt 16. In addition, joint stiffeners 24 are affixed beneath each bed member 4 and extended to the leading edge of cross channel member 6.

I claim:

A portable grinder carrier comprising a frame adapted to be attached for movement therewith to a piece of mobile farm machinery and adapted to receive a grinder thereon, said carrier frame having a bed to receive thereon the grinder, wheel standards supported on the ends of said bed and projecting upwardly therefrom and forming journals for mounting a vertically adjustable wheel, a front base cross channel member, upright frame members supported on the front base of the carrier and carrying pins for attaching the frame to the mobile farm machinery and cooperative with lifter arms on the mobile farm machinery to keep the grinder level, said bed being adapted to position the grinder whereby it may be driven by a belt from the mobile farm machinery, and means for applying tension to the belt drive comprising journal blocks slidably mounted for vertical movement between the upright members, a bar intermediate the journal blocks and having a drum longitudinally slideable thereon for engagement with the belt from the farm machinery to the grinder.

LE ROY CARLSON.
